CLAIM

The ornamental design for a bath pillow, as shown.

DESCRIPTION

FIG. 1 is a bottom front perspective view of a bath pillow; FIG. 2 is a top front perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The broken lines in the figures represent portions of the bath pillow which form no part of the claimed design.
